D11-151.

OR D14,226

EX

Design No. 14,226, dated August 21, 1883.

UNITED STATES PATENT OFFICE.

CHARLES NARDINI, OF SAN FRANCISCO, CALIFORNIA.

DESIGN FOR A VASE.

SPECIFICATION forming part of Design No. 14,226, dated August 21, 1883.

Application filed July 13, 1883. Term of patent 3½ years.

To all whom it may concern:

Be it known that I, CHARLES NARDINI, a subject of the King of Italy, residing at San Francisco, in the county of San Francisco and State of California, have invented and produced a new and original Design for Vases, of which the following is a specification, reference being had to the accompanying photograph, forming part thereof.

10 The leading features of my design consist in providing the exterior surface of a vase with a new and original demi or basso rilievo ornamentation, consisting of architectural configurations, tule-heads, twining vines, birds, and 15 Roman masks, and also in forming a vase with a small opening or neck, which is afterward expanded or extended outward horizontally and made waving in the direction of its circumference and somewhat curved in a radial 20 direction.

A is the base of my vase, and is made octagonal in plan, and has the top thereof ornamented with raised architectural figures. From this base rises the stem B, the main portion of which is ornamented with the representation of thick leaves placed points upward, and between which are placed representations of the heads or tufts of the tule-plant. From this stem rises the body or bowl C of 30 the vase, the lower part being ornamented similarly to the base of the stem, yet upon a larger scale. The main body of the vase is covered by twining grape-vines, which seem to hang or grow downward and display the 35 usual stems, leaves, tendrils, and bunches of fruit. About midway of the height of the vase's bowl I place the representation of small

birds, which stand upon the vine-stems, and are shown in the act of picking or eating the grapes. The upper part of the bowl is contracted so 40 as to form a neck, D, around which I place the representation of Roman masks or grotesque false-faces. The top of the vase, or that portion above the neck which forms the mouth E, is flared outward in a generally horizontal 45 direction, and is made waving in the direction of its circumference, as clearly shown in the accompanying photograph, and it also presents a waving line or surface, alternately rising and falling when viewed upon the edge. The outer 50 edge of this mouth is made scalloped, and is also corrugated upon its upper face. The Roman masks above referred to appear immediately beneath the raised or upwardly-curved portions of vase's mouth.

55 I claim—

1. The design for a vase or other similar article herein shown and described, the same consisting of a vase having a contracted neck, D, and an extended or flaring mouth, E, having a waving contour.

2. The design for a vase herein shown and described, the same consisting of the arrangement upon the exterior surface of the article of designs or representations in rilievo of architectural forms, tule-heads, vines, birds, and 65 Roman masks.

In testimony that I claim the foregoing I have hereunto set my hand and seal.

CHARLES NARDINI. [L. S.]
